UNITED STATES PATENT OFFICE

2,315,976

APPARATUS FOR OPERATING ON SHEET MATERIAL

Harold S. Method, East Chicago, Ind., assignor to Inland Steel Company, Chicago, Ill., a corporation of Delaware

Application April 14, 1941, Serial No. 388,531

18 Claims. (CL 164—68)

My invention, generally stated, relates to situations in which strip or sheet material, while being continuously fed, is operated on, particularly at intervals, in such a way as to interfere with the normal feed of the material, by exerting on the material beyond the feed means, either a retarding action or an accelerating action. Examples of such situations are those wherein the strip material is sheared at intervals into sheets, by shearing mechanism of the rotary type or the guillotine type, or is operated on by punching mechanism.

This application is a continuation in part of my pending application for United States Letters Patent Serial No. 381,578, filed March 3, 1941.

When the strip material is subjected, in accordance with common practice, to a retarding action such deformation of the material as to tend to impair the material, as for example crack the surface of the strip, and interfere with the maximum production of satisfactory product, results; and also when subject to the accelerating action the material is apt to become impaired.

The use for which I more particularly devised my invention, but without any intention of limiting the invention to such use, is in connection with the shearing of strip material, such as for example, and more particularly, steel strip, either hot or cold rolled, into the desired sheet lengths, involving the use of a so-called rotary shear associated with mechanism by which the strip to be sheared is continuously fed to the shearing mechanism which operates to cut the strip into sheets of a predetermined length.

Such a shearing mechanism, to meet the requirements in practice, must be capable of cutting sheets of widely varying lengths which, in the shearing of both the longer and shorter lengths, involves problems due to the fact that the rotary shear mechanism continuously operates and the strip is fed thereto by a continuous movement at constant speed which results, in the case of the longer sheets, in the exertion of such retarding action by the shearing mechanism on the continuously fed strip as to cause the strip to so deform as to impair the strip or cause its leading edge to follow around one of the rolls of the shearing mechanism instead of discharging straight through the shearing mechanism as desired, and in the case of the shorter lengths a tendency to the pulling of the strip through the feed rolls often damaging the strip; the retarding action referred to starting as soon as the shearing knives start to bite into the strip and continuing until the leading edge

of the strip disengages from the side of the shearing blade which it is caused to abut at the moment the sheet is severed from the strip.

My objects are to provide against such retarding action on the strip material interfering with the proper passage of the material through the apparatus employed in operating on the strip material, or damaging the strip material operated on; to provide against such accelerating action on the strip material exerting such pull on the strip material as would cause it to become damaged by the feed rolls or otherwise become damaged; to provide improvements in apparatus of the character above referred to whereby, by adjusting the apparatus, sheets of any desired predetermined length may be sheared from the strip; to provide for the making of such adjustments easily and quickly; to provide, in the use of the invention in connection with rotary shearing mechanism, against the possibility of the strip material becoming damaged by retarding action exerted against it and the possibility of the leading edge of the strip following around a roll of the shearing mechanism, thereby to provide for the proper delivery of the sheets from the shearing mechanism; to provide against the possibility of transmitting pull exerted on the strip material, as for example by the shearing mechanism when the machine is set for the cutting of the shorter length of sheets, to the portion of the strip between the feed rolls, to such degree as would cause the strip to be pulled through the feed rolls with likelihood of damage to the strip, or would cause the strip to be otherwise damaged; to provide for the shearing of the maximum number of sheets from the strip; and other objects as will be manifest from the following description.

Referring to the accompanying drawings:

Figure 1 is a fragmentary plan view of a combined strip-feeding mechanism and a shearing mechanism embodying my invention, and by which my improved method may be practiced.

Figure 1^a is a similar view of driving means for the mechanisms of Fig. 1, these two views being complementary, the structures shown therein joining along the irregular dot and dash lines in these two figures.

Figure 8 is a fragmentary sectional view of the shearing mechanism, taken at a line corresponding to the line 2 on Fig. 1 and viewed in the direction of the arrows, this view being enlarged to more clearly illustrate details.

Figure 9 is an enlarged sectional view taken at the line 9—9 on Fig. 1 and viewed in the direction of the arrows; and

Figure 10, a fragmentary sectional view taken at the line 10—10 on Fig. 9 and viewed in the direction of the arrows.

Referring to the particular illustrated embodiment of my invention the delivery end, by way of example, of a shear-approach table to which the long strips produced on a hot strip mill are delivered from the mill, is shown at 11 and in accordance with common practice is provided with sets of driven feed rolls, those at the delivery end of the table being shown at 12, upon which the strip 13 to be sheared into sheets, is supported and by which the strip is fed. In practice the table is usually much longer than the strips produced on the mill so that by the time the advance end of the strip has reached the delivery end of the table the strip is disengaged from the mill proper.

In front of the rollers 12 is a pair of upper and lower pinch rolls 14 and 15, respectively, mounted in a stand 16 in accordance with common practice, and driven as hereinafter described, the rolls 14 and 15 operating to feed the strip 13, which extends between these rolls, in the direction of the feathered arrow in Fig. 2.

Located in front of the pinch rolls 14 and 15 and in spaced relation thereto is a rotary shear mechanism 17 through which the strip 13 is continuously fed from the feed-rolls 14 and 15 and by which the strip is sheared into separate sheets (one of which is shown at 18) which are conveyed away by feed means 19 located in front of the shearing mechanism, one of the feed rolls of which and which may form one of the sets of rolls of a magnetic-roll feed mechanism commonly known in the art, being represented at 20, the sheets feeding to the feeding mechanism over a roller 21, the feeding mechanism 19 commonly operating at a higher speed than the feed-rolls 14 and 15.

The shearing mechanism shown is of a common and well known construction and therefore a general description thereof will suffice. It comprises generally stated, driven upper and lower rolls 22 and 23, respectively, journaled in a stand 24 to extend crosswise of the path of travel of the strip 13, these rolls being equipped with shearing blades 25 and 26, respectively, extending lengthwise thereof and projecting beyond the peripheries of these rolls. These rolls driven at different speeds because of their difference in diameter are driven at such speeds, respectively, in the directions of the arrows in Fig. 2, that the front surface 27 of the shearing blade 25 and the rear surface 28 of the shearing blade 26 meet and extend in the plane in which the axes of the two rolls 22 and 23 lie, in the lowermost position of the shearing blade 25 and the uppermost position of the shearing blade 26, as shown in Figs.

2 and 8, a position occupied by these blades immediately upon the severing of a sheet from the strip 13.

According to the requirements of the trade the sheets are required to be cut of greatly varying lengths, according to present practice of from 66" to about 300". The length of the sheets to be cut from the strip 13 is determined by the relation of the peripheral speed of the shearing rolls 22 and 23 to the speed of travel of the strip 13 to these rolls, viz., to the speed of rotation of the feed rolls 14 and 15, and thus an apparatus to fulfill the requirements referred to must be capable of adjustment to vary the speeds as required; preferably with the minimum loss of time.

The driving mechanism shown and which serves as a very satisfactory means for this purpose comprises a motor 29 the drive shaft 30 of which is operatively connected with the pinch rolls 14 and 15 for driving these rolls at the same speed through any desirable construction of selective-speed mechanism for varying the speed at which these rolls rotate, as for example a three-speed Maag gear reducer which is of well known construction, is represented at 32 and has selector means for setting this mechanism for any one of the three speeds. Accordingly the shaft 30 is directly connected with the rotary selector shaft 32a of the unit 32, the shaft 32a having splined thereon gears of different diameters shiftable, as a unit, by the operator from the outside of the casing of the unit, along the shaft 32a into intermeshed relation, respectively, with gears of different diameters fixed on a rotary shaft 32b of the unit 32, the shaft 32b being directly connected to the lower pinch roll 15 by a coupler 31.

By shifting the gears carried by the shaft 32a into one position along this shaft the shaft 32b will be driven at one speed, which may be termed intermediate speed, and by shifting these gears into other positions along the shaft 32a, the shaft 32b will be driven at a higher or a lower speed, respectively, than in said setting for intermediate speed.

The unit 32 also comprises an upper rotary shaft 32c which is geared to the shaft 32b to rotate at the same speed as the shaft 32b and is directly connected to the upper pinch roll 14 by a coupler 14a.

Thus provision is made by the unit 32 for driving the pinch rolls 14 and 15 and thus the strip fed by these rolls, at three different speeds selectively.

The shearing rolls 22 and 23 are operatively connected together in accordance with common practice so that applying driving force to the lower roll 23 will rotate both rolls in the directions of the respective arrows in Figs. 2 and 8 and cause the shearing blades 25 and 26 to meet as above described; the power for applying driving force to the lower roll 23 comprising gear mechanism connected with the roll 23 and located in a stationary gear housing 33 and driven by a Waterbury hydraulic unit 34 actuated from the shaft 30 through the medium of a speed reducing gear mechanism of any suitable construction represented generally at 35 and interposed between the unit 34 and the drive shaft 30.

The Waterbury hydraulic unit 34 is well known in the art and therefore does not need detailed description. It is sufficient to say that it comprises an hydraulic pump 36 actuated by the shaft 30 through a speed reducer unit 35 for

forcing fluid, to an hydraulic motor 37 which is actuated by this fluid, responsive to the flow of fluid thereto from the pump 38 determined by the setting of a valve control for this pump to vary the speed at which the motor 37 and therefore the shearing rolls 22 and 23 rotate, relative to the speed of operation of the pump 38.

The hydraulic unit referred to is not adequate for the driving of the shearing rolls 22 and 23 at the relatively high and relatively low speeds desired for the shearing of the shorter and longer sheet lengths, as for example sheet lengths of less than about 94 inches and more than about 196 inches, respectively, but by providing an additional control means, such as, for example, the unit 32 which operates to selectively drive the pinch rolls 14 and 15 at different predetermined speeds from the motor 29, such shorter and longer sheet lengths may be produced very satisfactorily; the gearing of the speed changer 32 being such that when adjusted by the selector means thereof, to the intermediate speed position above referred to it effects the drive of the pinch rolls 14 and 15, at such speed relative to the pump portion 36 of the unit 34 that sheets of any desired predetermined length within the range of about 94 inches to about 196 inches may be cut, under the control of the unit 34; and when adjusted to the high and low speed positions above referred to, effect the drive of the pinch rolls 14 and 15 at such high and low speeds, respectively, relative to the pump portion 36 that sheets of any desired predetermined lengths between the range of about 196 inches to about 300 inches and from about 66 inches to about 94 inches, respectively, may be cut under the control of the unit 34.

In the case of the production of sheets of a length within what may be termed the middle range of lengths, such as for example sheets of from about 94" length to sheets approximating 196" length, the apparatus in so far as it has been herein described, will operate reasonably satisfactorily to cut and properly deliver the sheets from the shearing mechanism without likelihood of such retarding action being exerted against the strip 13, by the shearing mechanism, as to cause the strip to become so deflected as to follow around the lower roll of the shearing mechanism or so deformed as to damage the strip, in the case of the cutting of the longer sheets within the middle range referred to; and without such pulling on the strip by the shearing mechanism 17 in the case of the cutting of the shorter sheets within the range referred to, as would cause the strip to become damaged by the feed rolls 14 and 15 or otherwise damaged. However, in the case of the production of sheets of lengths longer or shorter than the middle range of lengths above referred to, as for example sheets longer than about 196" and shorter than about 94", the mechanism in so far as above described, presents the objection, in the case of the cutting of the longer lengths of sheets that the retarding action exerted on the strip by the shearing mechanism frequently results in the strip becoming so deformed as to follow around the lower roll of the shearing mechanism instead of discharging straight through the shearing mechanism and also result in damage to the strip as by cracking it; and in the case of the shorter lengths of sheets the pull exerted by the shearing mechanism on the strip is such as to pull the strip through the feed rolls 14 and 15,

thus damaging it or otherwise damaging the strip.

In further explanation of the action which takes place in the shearing of a sheet from the strip and the objectionable results produced in the shearing of the above referred to short and long lengths of sheets, it may be stated that the longer the sheet to be produced, the slower the travel of the shearing blades 25 and 26 relative to the speed at which the strip is fed to the shearing mechanism, and the shorter the sheets to be produced the faster the movement of the shearing blades relative to the speed at which the strip is fed to the shearing mechanism.

The action of the cooperating shearing blades 25 and 26 in shearing a sheet from the strip 13 is not instantaneous inasmuch as the shearing blades, in moving through arcuate paths at opposite sides of the strip, engage and press against these opposite sides by a progressive action, pressing more deeply into the strip as they continue to rotate, until they reach a position in which the adjacent edges of their faces 27 and 28 approximately meet. Thus during the period from the initial engagement of the shearing blades with the strip to the actual severing of the strip, the strip is rigidly held by the shearing blades.

Therefore, in the case of the cutting of the shorter lengths of sheets the shearing blades in engaging the strip exert objectionable pull on the relatively slowly fed strip tending to pull it through the feed rolls; and in the cutting of the longer lengths of sheets the above-referred-to clamping action of the relatively slowly rotating shearing blades presents a resistance to the forward movement of the strip under the action of the feed rolls 14 and 15, which resistance continues to be exerted on the strip, because of the abutment of its leading edge against the side of the lower shearing blade 26, until this blade, in traveling in its arcuate path, moves out of the path of straight-line movement of the strip; the resistance thus presented to the leading edge of the strip so deforming it, unless provision is made to prevent such deformation, as to cause the strip, under the impelling action of the feed rollers 14 and 15, to follow around the lower roll 23 of the shearing mechanism, instead of discharging straight through the shearing mechanism and also to damage the strip.

According to one phase of my invention I provide against the occurrence of the above noted objections, employing, in accordance with the preferred embodiment of my invention, mechanism of which the following is a description.

Located between the feed-roll stand 16 and the shearing mechanism 17 and closely adjacent the latter and at a considerable distance from the feed-roll stand, is a roll stand 38 comprising rolls 39 and 40 extending transversely of the path of movement of the strip 13, the lower roll 40 being shown as mounted in stationary journal-bearings and the upper roll 39 in vertically slideable journal-bearings 41. The rolls 39 and 40 are shown as positively driven by the motor 29 in the direction of travel of the strip 13, and at the same peripheral speed as the rolls 14 and 15 by means of a belt 42 trained about a pulley 43 secured to the shaft 32c and about a smaller pulley 44 on a shaft 46 journaled in a support 45 and connected with the upper roll 39 by a universal coupling 47 and intermeshing gears 48 and 49, the gear 48 being fixed on the shaft 46 and the

gear 48 fixed on a shaft 50 operatively connected with the lower roll 40.

The journal-bearings 41 for the upper roll 38 are shown as connected with the movable member 51 of solenoid devices 52 stationarily mounted on the frame of the roll stand 38, which serve when energized to raise the upper roll 38 into a position in which it is spaced from the lower roll 40 a greater distance than the thickness of the thickest strip 13 to be operated on, as for example spaced about 1".

Located between the roll-stands 16 and 38 are means 53 for exerting upward pressure against the strip 13 deflecting it upwardly into looped condition. The means shown for this purpose comprise a pair of rollers 54 and 55 extending crosswise of the path of movement of the strip 13 adjacent its under side and preferably driven in the direction of travel of the strip as by a light power motor 54a connected with these rollers by gearing in the case 54b. The rollers 54 and 55 are rotatably mounted in a frame 56 on which the motor 54a and the gear case 54b are mounted, the frame 56 being supported on a stationary part of the apparatus to swing about a horizontal axis for movement of the roller 54 into and out of a position in which its uppermost surface extends above the normal path of movement of the strip 13, an example of such position of the frame 56 and roller 54 being shown by full lines in Fig. 2, the lowermost position of these parts being shown by dotted lines in this figure.

The frame 56 is shown as comprising end members each formed of a pair of angle irons 57 extending lengthwise of the apparatus and positioned in back-to-back relation, but spaced apart, a tubular bearing member 58 rigidly secured to the angle irons 57 of each pair; a pair of spaced apart angle-irons 59 and 60 extending crosswise of the apparatus and secured to the innermost ones of the angle irons 57 and journaling members 61 for the shafts 54 and 55 mounted on the pairs of angle irons 57.

The pivoting support for the frame 56, located adjacent its right-hand edge in Figs. 2 and 6, comprises a stationary shaft 62 rigidly secured at its ends of ears 63 rising from the stationary frame of the apparatus, the shaft 62 extending through the depending flanges of the angle-irons 57 and the bearing members 58, the latter being journaled on the shaft 62. Between the angle irons 57 of each pair and secured to the stationary frame of the apparatus, is a channel-block 64 shown as provided with a pad 64a on its upper surface forming a rest for the rock-frame 56 in its lowermost position.

Associated with the frame 56 are means for exerting force against the frame for rocking it on its pivotal support clockwise in Fig. 7 for looping the strip 13, these means being preferably of such construction that the force they exert against the frame 56 is a yielding force variable in degree, as desired, under the control of the operator.

The particular construction of means shown for this purpose comprises a fluid-pressure piston and cylinder device 65 trunnioned at 66 on angle-irons 67 supported on the stationary frame of the apparatus, the piston rod 68 of which is pivotally connected at 69 to a pair of spaced angle irons 70 secured to the angle irons 59 and 60 and receiving between them the outer end of the piston-rod. The piston of device 65 is operated by elastic fluid pressure, such as for 75

example compressed air, supplied to the cylinder 71 of this device from any suitable source, venting of the operating fluid from the cylinder 71 being effected in any suitable way under 5 the control of the operator as is well known to those skilled in the art relating to fluid-pressure-operated piston and cylinder devices. The machine shown is also provided with a set of rollers 100 and 101 in front of the frame 56 and 10 preferably driven in the direction of feed of the strip by a light power motor 102 connected with the rollers 100 and 101 by gear mechanism in the case 103.

Preliminary to the starting of the shearing 15 operation the hydraulic unit 34 and the selector unit 32 are conditioned, for causing the shearing rolls 22 and 23 to rotate at the proper speed, relative to the speed of the feed-rolls 14 and 15, for shearing the strip 13 into sheets of the desired length; by way of example, the speed-reducer unit 32 being set in its low-speed-driving position for cutting sheets from about 66" lengths to about 94" lengths; in its high-speed-driving position for cutting sheets from about 20 196" lengths to about 300" lengths and in its intermediate-speed driving position for cutting sheets from about 94" lengths to about 196" lengths, the control of the hydraulic unit 34 being manipulated for close control of the speed 25 30 of the shearing rolls 22 and 23 for cutting the sheets to the exact lengths desired, any corrections of adjustment of the hydraulic unit 34 to produce sheets of the accurate predetermined length being made after the trial cutting of the 35 first sheet.

In using the apparatus for the shearing of the strip 13 into sheets of such long lengths (as for example sheets approximating a length of 196" and longer,) that the strip-speed is so much 40 faster than the speed of the shearing rolls 22 and 23 that the retarding action by the shearing mechanism on the strip produced by the grip of the shearing blades against the strip and the engagement of the side of the relatively slowly moving lower shearing blade with the leading edge of the strip occurring instantly following a sheet-shearing operation (Figs. 2 and 3), is such that, unless prevented, it tends to cause the strip to become so deformed that the leading edge portion of the strip follows around the lower shearing roll as this roll continues to operate, instead of discharging straight through the shearing mechanism and also tends to crack the frame 56, carrying the rollers 54 and 55, is brought into action by the operator, by supplying 45 actuating fluid pressure to the cylinder 71 of the piston and cylinder device 65 which exerts force tending to move the roller 54, at its upper 50 surface, above the normal path of travel of the strip 13 and thereby tends to deflect the strip upwardly into a relatively long loop between the feed-rolls 14 and 15 and the rolls 38 and 40 which latter are spaced apart as above referred to, in 55 which position the upper roll 38 serves merely as a means for preventing upward movement of the strip at this point when force is applied to the strip tending to deflect it into loop form. Therefore, during the mutual engagement of the strip 13 and the shearing blades 25 and 26 (which latter are moving slower than the feed of the strip from the start of the engagement of the shearing blades with the strip until the lower shearing blade 26 has moved to a position in 60 which it is withdrawn by its movement in an 65

arcuate path from engagement with the leading edge of the strip after the sheet-cutting operation, during which time resistance is offered by the shearing mechanism to the free travel of the strip), the continuing force applied to the strip by the piston and cylinder strip-looping device 65 serves to so relieve the strip of the force exerted against it by such retarding action, by the looping of the strip between the feed rolls 14 and 15 and the rolls 39 and 40, that the portion of the strip between the rolls 39 and 40 and the shearing mechanism remains substantially straight whereby the strip moves straight through the shearing mechanism without following around the lower shearing roll 23 and the strip between the rolls 39 and 40 and the feed rolls 14 and 15 is in the form of such long length that cracking of the strip is avoided.

As will be understood the operator will vary the fluid pressure supplied to the cylinder 11 in accordance with the weight of the loop portion of the strip 13, depending on the gauge and width of the strip but this fluid pressure should always be sufficient to insure the compensating, to the degree desired, for the resistance afforded by the shearing mechanism 17 to the movement of the strip described, even to the extent of actually drawing back the leading edge of the strip from engagement with the lower shearing blade 26 at the instant of shear, but not sufficiently great as to cause the strip, at the portion thereof engaged by the feed-rolls 14 and 15, to be pulled with such force that it will slip between these rolls and thus present likelihood of damage.

The gist of my invention as to one phase thereof, consisting in relieving the strip of the objectionable retarding action by the shearing mechanism as stated, it will be understood that the loop thrown into the strip to relieve this action need not be thrown therein throughout the travel of the strip through the shearing mechanism 17 but only simultaneously with the engagement of the shearing mechanism with the strip, this being performed in any suitable way.

In the shearing of the strip 13 into sheets of such short lengths, as for example sheets approximating a length of 94" and shorter, that the strip speed is enough slower than the speed of the shearing rolls 22 and 23 as to cause the shearing blades 25 and 26 in engaging the strip, to exert a pull on the strip which, if not relieved, would pull the strip in the feed-rolls 14 and 15 and damage the strip, the strip-looping mechanism 53 is also highly useful as it serves to yield, responsive to said pull on the strip, thus causing the looped portion of the strip to approach flat condition and prevent the tension of the strip at the feed-rolls 14 and 15 to be sufficient to pull the strip in these feed rolls, the looping mechanism 53, as soon as the sheet has been sheared from the strip, restoring the strip to normal looped condition.

To insure the production of the maximum number of sheets from any given length of strip I provide for the shearing from the tail end of the strip 13, when such tail end is of a length greater than that of the sheets being sheared from the strip but less than double the length of such sheets, the extra sheet obtainable therefrom, whereby the waste therefrom is less than such sheet length.

This I accomplish by transforming the roll stand 38 from a mere guide for the strip 13 (serving to hold the strip down at this point), to a positive feed means therefor, by deenergizing the sole-

noid devices 52 to permit the roll 39 to lower upon the strip 13, when the trailing edge of the strip closely approaches the feed-rolls 14 and 15, whereby the strip, before leaving these feed-rolls, is engaged and driven by the rolls 39 and 40 to the shearing mechanism 17. This may be accomplished in any suitable way, as for example as shown, by providing target electrical switch mechanism located to the rear of, and closely to, the roll stand 38 and in circuit with the solenoid devices 52 and the source of current supply (not shown) and by which the switch is held closed during the travel of the strip along the target device of the switch mechanism, but automatically opens when the trailing edge of the strip passes the target device.

The target switch mechanism shown comprises a rotary shaft 72 (Figs. 1, 9 and 10) carrying a target device 73 which registers with a slot 74 in the bed 75 of the apparatus, the shaft being coupled to a switch device shown generally at 76 which would be connected in circuit with the coils of the solenoid devices 52 and is actuated to and from circuit-closing position by rotation of the shaft 72, in opposite directions, respectively, a spring (not shown) associated with the shaft 72 tending to rotate this shaft to circuit-open position in which position the target device 73 projects upwardly through the slot 74 as shown by full lines in Fig. 10. As will be understood the target device 73 is held in circuit-closed position so long as the strip is superposed on the bed 75 of the apparatus extends in registration therewith, but as soon as the trailing edge of the strip passes beyond the target device 73 the latter swings upwardly under the action of the spring referred to, permitting the shaft 72 to be rotated by the spring to a position in which the circuit through the solenoid devices 52 are broken, whereupon feeding of the tail end of the strip by the rolls 39 and 40 of the stand is initiated.

While I have illustrated and described a particular construction of mechanism and certain modifications thereof, embodying my invention and by which my novel method may be practiced, I do not wish to be understood as intending to limit the invention thereto as the structure may be further modified and altered and the invention embodied in other forms of structure and my novel method practiced by the use of other constructions without departing from the spirit of my invention.

What I claim as new and desire to secure by Letters Patent, is:

1. In apparatus comprising means for feeding sheet material and means to which said material is fed and operating on said material during the feeding of said material and in such operation exerting an accelerating action on the material and reciprocating piston and cylinder fluid-pressure means between said first and second named means for yieldingly exerting force against the material in a direction to deflect the material during said accelerating action.

2. In apparatus comprising means for feeding sheet material and means to which said material is fed and operating on said material during the feeding of said material and in such operation exerting an action on the material at variance with the speed at which the material is fed by said first-named means, reciprocating piston and cylinder fluid pressure means between said first and second named means operative during said action of said second named means for yieldingly

exerting force on the sheet material in a direction to deflect the material.

3. In apparatus comprising means for feeding sheet material and means to which said material is fed and operating on said material during the feeding of said material and in such operation exerting an action on the material at variance with the speed at which the material is fed by said first-named means, reciprocatory piston and cylinder fluid pressure means between said first and second named means for yieldingly exerting force on the sheet material in a direction to deflect the material, and means between said second and third named means and adjacent said second named means for restraining deflection of the material at this point by said third named means.

4. In apparatus comprising means for feeding sheet material and means to which said material is fed and operating on said material during the feeding of said material and in such operation exerting either a retarding action or an accelerating action on the material, reciprocatory piston and cylinder fluid pressure means between said first named means and said second named means operative during said action of said second-named means for yieldingly exerting force against the sheet material in a direction to deflect the material.

5. In apparatus comprising means for feeding sheet material and means to which said material is fed and operating on said material during the feeding of said material and in such operation exerting either a retarding action or an accelerating action on the material, reciprocatory piston and cylinder fluid pressure means between said first-named means and said second-named means for yieldingly exerting force against the sheet material in a direction to deflect the material, and means between said second and third named means and adjacent said second named means for restraining deflection of the material at this point by said third-named means.

6. In apparatus comprising a rotary shearing mechanism and feed means for feeding sheet material to said shearing mechanism, reciprocatory piston and cylinder fluid pressure operated means between said shearing mechanism and said feed means for exerting force against the sheet material for deflecting it at a time when the knives of said shearing mechanism are in engagement with the sheet material.

7. In apparatus comprising a rotary shearing mechanism and feed means for feeding sheet material to said shearing mechanism, means between said shearing mechanism and said feed means for yieldingly exerting force against the sheet material at a time when the knives of said shearing mechanism are in engagement with the sheet material for deflecting the sheet material comprising a rock frame having a sheet engaging portion, and means for rocking said frame against the sheet material, the apparatus being free of restraint to the longitudinal movement of the sheet material under the action of the knives of said shearing mechanism.

8. In apparatus comprising a rotary shearing mechanism and feed means for feeding sheet material to said shearing mechanism, reciprocatory piston and cylinder fluid pressure means between said shearing mechanism and said feed rolls movable against the material for exerting force against the sheet material for deflecting it, and means between said second named means

and said shearing mechanism for restraining deflection of the sheet material at this point.

9. In apparatus comprising a rotary shearing mechanism, feed means for feeding sheet material to said shearing mechanism and means for driving said shearing mechanism at different speeds relative to said feed means, reciprocatory piston and cylinder fluid pressure means operating automatically in the shearing of long sheets from the sheet material, during which operation the shearing mechanism operates at a much slower speed than said feed means, to deflect the sheet material for preventing such forcing of the leading edge of the sheet material against the shearing blade of the lower roll of the shearing mechanism under the action of said feed means, as to cause the sheet material to follow around said roll.

10. In apparatus comprising shearing mechanism and feed means for feeding sheet material to said shearing mechanism, means for looping the sheet material between said shearing mechanism and said feed means and mechanism between said shearing mechanism and said second-named means controllable to serve selectively as means for restraining deflection of the sheet material at this point and as a feed means for the sheet material, and means controlled by the position of the sheet material for controlling the conditioning of said second-named mechanism.

11. In apparatus comprising a rotary shearing mechanism, feed means for feeding sheet material to said shearing mechanism and a power device, means operated by said power device for driving said feed means selectively at different speeds relative to said power device and means for driving said shearing mechanism from said power device at different speeds selectively relative to said power device, said second-named means and said third named means being adjustable independently of each other for different speeds and serving, respectively, as coarse control means and fine control means for producing a selected speed differential between said feed means and said shearing mechanism.

12. In apparatus comprising a rotary shearing mechanism, feed means for feeding sheet material to said shearing mechanism and a power device, means operated by said power device for driving said feed means selectively at different speeds relative to said power device, and a Waterbury hydraulic unit for driving said shearing mechanism from said power device at different speeds selectively relative to said power device, said second named means and said Waterbury unit being adjustable independently of each other for different speeds and serving, respectively, as coarse control means and fine control means for producing a selected speed differential between said feed means and said shearing means.

13. In apparatus comprising a rotary shearing mechanism, feed means for feeding sheet material to said shearing mechanism and a power device, means for driving said shearing mechanism and said feed means by said power device comprising means operated by said power device and interposed between said shearing mechanism and said power device and operative, when used alone, to control the length of sheets cut within a certain range only of lengths and means whereby sheets of less length and sheets of greater length than those within said certain range, may be selectively sheared by said shearing mechanism by the power supplied to said shearing mechanism through said third named means.

14. In apparatus comprising a rotary shearing mechanism, feed means for feeding sheet material to said shearing mechanism and a power device, means for driving said shearing mechanism and said feed means by said power device comprising a Waterbury hydraulic unit operated by said power device and interposed between said shearing mechanism and said power device and operative when used alone to control the length of sheets cut within a certain range only of lengths and means whereby sheets of less length and sheets of greater length than those within said certain range, may be selectively sheared by said shearing mechanism by the power supplied to said shearing mechanism through said Waterbury unit.
15. In apparatus comprising means for feeding sheet material and means to which said material is fed and operating on said material during the feeding of said material and in such operation exerting an action on the material at variance with the speed at which the material is fed by said first-named means, means between said first and second-named means for yielding exerting force on the sheet material in a direction to deflect the material, said last-named means comprising a roll which engages the sheet material and means for driving said roll in the direction of travel of the material.
16. In apparatus comprising a rotary shearing mechanism and feed means for feeding sheet material to said shearing mechanism, means between said shearing mechanism and said feed means for yieldingly exerting force against the sheet material at a time when the knives of said shearing mechanism are in engagement with the sheet material for deflecting the sheet material comprising a rock frame having a sheet engaging roll.
17. In apparatus comprising means for feeding sheet material and means to which said material is fed and operating on said material during the feeding of said material and in such operation exerting an action on the material at variance with the speed at which the material is fed by said first-named means, reciprocatory piston and cylinder fluid pressure means between said first and second-named means operative, during said action of said second-named means, by the application of fluid pressure to said mechanism for yieldingly exerting force on the sheet material in a direction to deflect the material.
18. In apparatus comprising means for feeding sheet material and means to which said material is fed and operating on said material during the feeding of said material and in such operation exerting an action on the material at variance with the speed at which the material is fed by said first-named means, means between said first and second-named means operative during said action of said second-named means for yieldingly exerting force on the sheet material in a direction to deflect the material, said last-named means being movable on the apparatus to a position in which the sheet material in straight condition may be positioned across said means and the apparatus being free of restraint to the longitudinal movement of the sheet material under the action of the knives of said shearing mechanism.

HAROLD S. METHOD.

CERTIFICATE OF CORRECTION.

Patent No. 2,315,976.

April 6, 1943.

HAROLD S. METHOD.

It is hereby certified that error appears in the printed specification of the above numbered patent requiring correction as follows: Page 2, second column, line 6, after "from" insert --about--; page 4, first column, line 48, for "of" before "ears" read --to--; page 5, second column, line 72, claim 2, for "reciprocally" read --reciprocatory--; page 7, first column, line 24, claim 15, for "yielding" read --yieldingly--; and that the said Letters Patent should be read with this correction therein that the same may conform to the record of the case in the Patent Office.

Signed and sealed this 18th day of May, A. D. 1943.

Henry Van Arsdale,

Acting Commissioner of Patents.

14. In apparatus comprising a rotary shearing mechanism, feed means for feeding sheet material to said shearing mechanism and a power device, means for driving said shearing mechanism and said feed means by said power device comprising a Waterbury hydraulic unit operated by said power device and interposed between said shearing mechanism and said power device and operative when used alone to control the length of sheets cut within a certain range only of lengths and means whereby sheets of less length and sheets of greater length than those within said certain range, may be selectively sheared by said shearing mechanism by the power supplied to said shearing mechanism through said Waterbury unit.
15. In apparatus comprising means for feeding sheet material and means to which said material is fed and operating on said material during the feeding of said material and in such operation exerting an action on the material at variance with the speed at which the material is fed by said first-named means, means between said first and second-named means for yielding exerting force on the sheet material in a direction to deflect the material, said last-named means comprising a roll which engages the sheet material and means for driving said roll in the direction of travel of the material.
16. In apparatus comprising a rotary shearing mechanism and feed means for feeding sheet material to said shearing mechanism, means between said shearing mechanism and said feed means for yieldingly exerting force against the sheet material at a time when the knives of said shearing mechanism are in engagement with the sheet material for deflecting the sheet material comprising a rock frame having a sheet engaging roll.
17. In apparatus comprising means for feeding sheet material and means to which said material is fed and operating on said material during the feeding of said material and in such operation exerting an action on the material at variance with the speed at which the material is fed by said first-named means, reciprocatory piston and cylinder fluid pressure means between said first and second-named means operative, during said action of said second-named means, by the application of fluid pressure to said mechanism for yieldingly exerting force on the sheet material in a direction to deflect the material.
18. In apparatus comprising means for feeding sheet material and means to which said material is fed and operating on said material during the feeding of said material and in such operation exerting an action on the material at variance with the speed at which the material is fed by said first-named means, means between said first and second-named means operative during said action of said second-named means for yieldingly exerting force on the sheet material in a direction to deflect the material, said last-named means being movable on the apparatus to a position in which the sheet material in straight condition may be positioned across said means and the apparatus being free of restraint to the longitudinal movement of the sheet material under the action of the knives of said shearing mechanism.
